UNITED STATES PATENT OFFICE.

ELMER E. STONER, OF STROUDSBURG, PENNSYLVANIA.

ICE-HARVESTER.

1,115,613.

Specification of Letters Patent.

Patented Nov. 3, 1914.

Application filed February 27, 1912. Serial No. 680,160.

To all whom it may concern:

Be it known that I, ELMER E. STONER, a citizen of the United States, residing at Stroudsburg, in the county of Monroe and State of Pennsylvania, have invented new and useful Improvements in Ice-Harvesters, of which the following is a specification.

The general object of the invention is to minimize the time heretofore required to 10 harvest ice. And to this end the invention consists in an ice harvester which is adapted to move automatically in a required direction on the ice field, and, while progressing between two points on the said field, cut 15 the ice in two directions.

Other objects will appear and be better understood from that embodiment of my invention of which the following is a specification, reference being had to the accompanying drawings forming a part hereof, 20 in which;

Figure 1 is a side elevation of one embodiment of my invention. Fig. 2 is a plan of the same. Fig. 3 is a rear end elevation. Fig. 4 is a view similar to Fig. 2 with parts 25 removed and broken away to disclose the disposition of portions of the transmission mechanism. Fig. 5 is a view partly in side elevation and longitudinal section. Fig. 6 is a vertical cross section approximately on the line 6—6 of Fig. 5. Fig. 7 is a view similar to Fig. 6 but on the line 7—7 of Fig. 5. Fig. 8 is a detail plan of the transmission mechanism. Fig. 9 is a view similar to Fig. 8 but showing the parts in neutral position. Fig. 10 is a vertical longitudinal section approximately on the line 10—10 of Fig. 8. Fig. 11 is a vertical cross section approximately on the line 11—11 of Fig. 10. Fig. 12 is a vertical cross section on the line 40 12—12 of Fig. 8. Fig. 13 is a fragmentary detail in side elevation of the controlling device for the propeller. Fig. 14 is a fragmentary detail of one of the guides and its 45 control. Fig. 15 is a detail partly in section and elevation of the control for the lateral propellers. Fig. 16 is a side elevation of a modified form of harvester. Fig. 17 is a plan of the same. Fig. 18 is an end 50 elevation of the same. Fig. 19 is a detail of the lock. Fig. 20 is a detail of the latch. Fig. 21 is a detail perspective of the keeper.

The supporting or main frame, *a*, is suitably adapted, such as by providing runners

5—5 of suitable material such as angle iron, 55 for travel on an ice field, and its base area is such as to prevent the machine from toppling laterally while in use. To each of the runners 5—5 there is secured a series of spaced uprights 6—6, of suitable construction and preferably of metal, which have their upper ends connected to the side portions 7—7 of the platform 8 and serve as supports for the said platform.

The motor 9 which is herein shown to be 65 of the internal combustion type (although other types may be employed) has its base 10 suitably secured to the medial portion of the platform 8 and is arranged so that its crank shaft 11 will extend longitudinally of 70 the frame *a*.

A suitable connection, such as by means of sprocket wheels 12 and 13 secured respectively to the crank shaft 11 and stub shaft 14, and a sprocket chain 15, is established 75 between the said crank shaft 11 and the stub shaft 14 which has bearings in suitable hangers 16—16 suitably connected to a suitable support or supports, such as the platform 8. 80

Suitable means such as a bevel gear wheel 17, fixed to the stub shaft 14, bevel gear wheels 18—18 loose on a counter-shaft 19 and meshing with the bevel gear 17 and a clutch 20 splined on the counter-shaft 19, 85 is employed for transmitting rotary movement in opposite directions from the stub shaft 14 to the counter shaft 19 which is journaled in bearings 21, one of which is shown in Fig. 1 and held supported by truss bars 22—22 which are suitably connected to any convenient portion of the frame, such as the runners 5 and sides 7—7 of the platform 8.

The hangers 23—23 shown in Figs. 4 and 5 95 are suitably connected to any convenient portion of the structure such as to the platform 8, and are suitably adapted to provide bearings for a short shaft 24 disposed slightly above and suitably connected, such as by 100 means of a spur gear wheel 25 meshing with the pinion 26, to the counter-shaft 19 to which the pinion is suitably fixed.

By any suitable means such as sprocket wheels 27—27 fixed to the short shaft 24, 105 sprocket chains 28—28 and sprocket wheels 29—29, rotary movement is transmitted to the propeller shafts 30—30 journaled in

draw heads 31—31 arranged in depending guides 32—32 suitably connected to the corner portions of the frame *a*.

Suitable propeller wheels such as are indicated by 33—33, are suitably fixed to the shafts 30—30 and the spurs or teeth 34 of these wheels are normally held in spaced relation to the ice by suitable means such as springs 35—35 which are arranged in yokes 36—36 and which form supports for the draw heads as shown in detail in Fig. 13.

Cam shafts 37—37 have bearings in suitable supports such as arms 38—38 connected to the ends 39—39 of the platform 8 and in the upper portions of the guides 32—32, and are operated by suitable means such as pinions 40 meshing with rack bars 41—41 confined in guides 42—42 suitably connected to a convenient portion of the structure, such as the frame *a*. By preference the cam shafts are connected so as to be operated simultaneously. Any improved means may be employed for effecting this structure such as by providing the rack bars 41—41 with lateral projections 43—43 to which are connected links 44—44 which connect with rock arms 45—45 on a rock shaft 46, journaled in suitable bearings 46^a and suitably connected such as by means of a link 47, which connects one of the rock arms 45, with an operating lever 48 fulcrumed on the rear end portion of the platform 8 and securable in any of its moved positions by a latch and rack structure indicated generally by 49, and as shown in Figs. 2 and 3. The cams 50—50 on the cam shafts 37—37 contact with vertically extending offset portions 51—51 on the draw heads 31—31. Thus, when the parts are positioned as shown in Fig. 1, the draw heads 31 will be held to the lower ends of the guides by the cams 50. In this position the springs 35 will be tensioned and the propeller wheels 33 adjusted so as to contact with the ice. If in order

to adjust the parts in these positions, it became necessary to move the operating lever forwardly or away from the operator's seat 52, then when the operating lever is moved rearwardly or in the opposite direction the portions of the cams as shown contacting with the draw heads in Fig. 1, will move upwardly from the draw heads, thus enabling the springs 35 to force the draw heads upwardly and until the propeller wheels are raised clear of the ice.

The clutch 20 is operated by suitable means such as a horizontally disposed bell crank 53, one of the arms of which is adapted to oscillate an arm 54 pivotally connected as at 55, to the platform 8 and suitably adapted at its lower end for shifting the clutch 20. A connecting rod 56 has one end slidingly fitted in the bell crank 53 and has spaced heads 57—57 suitably secured there-

65 to and between which and the bell crank are

interposed springs 58—58, either of which is sufficiently strong so as not to yield when the connecting rod is operated by the operating lever 59 fulcrumed on the rear end portion of the platform 8 and provided with suitable means such as a latch 60, to adjustably secure it to a rack 61.

When the operating lever 59 and the parts connected thereto are moved so as to throw the clutch from the position shown in Fig. 9 to that shown in Fig. 8, and with the motor in operation and the propeller wheels lowered as shown in Fig. 1, the machine will move in a straight line on the ice until such time as the propeller wheels are raised by the instrumentalities previously described. In this connection it will be observed that not only the progressive movement but also the direction of such progressive movement of the machine, is controlled by the clutch 20.

The oppositely extending saw carrying frames *b* and *c* have their opposite sides 62—62 swingingly mounted on or otherwise suitably connected to suitable supports such as the opposite end portions of the counter-shaft 19. These saw frames which extend longitudinally of the main frame carry at their forward end portions, shafts 63—63 which have one end portion projecting laterally beyond one side of the frame as shown in Fig. 4. To these projecting end portions are suitably fixed the circular saws 65—65. A suitable connection such as by means of pulleys 66—66 fixed to the counter shaft 19, belts 67—67 and pulleys 68—68, is established between the counter shaft 19 and the saw shafts 63.

Normally, the saw carrying frames incline downwardly so as to hold the saws in contact with the ice and by twisting one of the belts 67 as shown in Fig. 4, one of the saws is caused to rotate in a direction opposite to that of the other saw.

The frames are preferably swung independently of each other by suitable means such as rock shafts 69 and 70 which are suitably connected such as by crank arms 71—71 and links 72—72 to the sides 62—62 of the frames *b* and *c*. A suitable connection such as by means of a crank arm 73 and a link 74, is established between the rock shaft 70 and an operating lever 75 fulcrumed on the rear portion of the platform 8. A suitable connection such as by means of a crank arm 76, and a link 77 is established between the rock shaft 69 and an operating lever 78 fulcrumed on the rear end portion of the platform 8 and adjacent to the operating lever 75. The operating levers 75 and 78 have suitable latches 79 and 80 which coöperate with racks 81 and 82 to secure the levers in any of their adjusted positions.

When the harvester is placed upon the

125

130

ice and propelled by the wheels 33—33 the saws 65—65 will cut the ice in a line parallel to the direction of movement of the harvester. During the progression of the harvester in making the initial cut it is not necessary to use both saws, therefore, under normal conditions the parts are arranged as shown in Fig. 1 when the harvester is moving to the left in said figure. The saws will 10 now rotate in the direction of the arrows and the rear saw will cut the ice. When the harvester is moving in the opposite direction or to the right, the positions of the saws 65—65 will, of course, be reversed. 15 After the making of the initial cut the propeller wheels 83—83 operate to shift the harvester laterally and until the saws 65—65 are removed from the initial cut for a distance equal to the standard length of a cake 20 of ice.

The shaft 84 to which the propeller wheels 83—83 are suitably fixed, extends longitudinally of the frame and is journaled in arms 84a—84a which are loose upon a shaft 86 25 journaled in the hangers 85—85, depending from any suitable portion of the frame, such as the platform 8, as shown in Figs. 3, 4, 5 and especially in Figs. 6 and 7 of the drawings. The shaft 84 which is by preference 30 positioned below and parallel with the stub shaft 14, is suitably connected such as by a sprocket 87, a sprocket chain 88 and a sprocket 89, with the shaft 86, which latter is also suitably connected such as by the 35 sprocket 90, the sprocket chain 91 and a sprocket 92, with the stub shaft 14.

The draw heads 93—93 in which the shaft 84 rotates, have their vertical draw rods 94—94 slidably fitted in spaced guides 40 95—95 formed with brackets 96—96 suitably secured to and depending from any convenient portion of the frame, such as the platform 8. The heads 98—98 which are suitably secured to the rods 94—94, bear 45 upon the springs 97—97 which operate to yieldingly hold the lateral propellers 83—83 in contact with the ice. The shafts 99—99 which are journaled in the lugs 100—100 on the brackets 96—96, have levers 101—101 50 which bear on the upper ends of the draw rods 94. The cranks 102—102 which are fixed to the shafts 99—99, are suitably adapted for loosely receiving the connecting rod 103, which has suitably secured to it, heads 55 104—104 which abut the cranks 102 and operate to move the same, whereby, to cause the lever 101—101 to depress the draw heads and lower the propeller wheels 83—83 into contact with the ice when the foot lever 105 60 fulcrumed on the rear portion of the platform 8 and connected by a link 106 to the connecting rod 103, is pressed in one direction. If desired, a suitable latching device (not shown) may be employed for locking 65 the foot lever 105 in any of its adjusted po-

sitions, or the latch may be eliminated as shown, so that when pressure is removed from the said lever, the springs 97 will operate to restore it to its normal position and lift the lateral propellers 83.

Either prior to or simultaneously with the lateral shifting of the harvester, the combined guides and stops 107—107 are permitted to descend into contact with the ice so as to enter the cut and bear on the edge 70 of the ice, whereby, to indicate to the operator that the machine has been moved laterally sufficiently far, and to prevent any tendency of the machine to move laterally in one direction, while making the subsequent cut. These guides may be of any suitable construction and are slidably fitted in brackets 108—108 which depend from arms 109—109 which are braced by struts 110—110, the said arms extending beyond 80 the saws 65—65 for a distance equal to the standard length of a cake of ice, or substantially so. Suitable elements such as springs 111—111 operate to force the guides 107 downwardly as shown in Fig. 1 and the 90 crank shafts 112—112, which are journaled in bearings 113—113 and connected to the guides and to a link 114, are adapted to lift the guides when the link is operated by suitable means such as a rock arm 115, on a 95 rock shaft 116 journaled in any suitable portion of the main frame 8 and connected to a foot lever 117, by any suitable means such as a connecting rod 118.

The harvester thus far described is adapted for self movement on the field of ice, for cutting the ice as it moves and for shifting laterally for a required distance after the making of a cut of required length. We are now coming to a description of one embodiment of suitable mechanism, which, after the harvester has been shifted laterally, the parts adjusted and the clutch 20 thrown so as to cause the harvester to travel in a direction opposite to that in which it traveled 100 in making the first cut, to cut the ice preferably at right angles to the initial and subsequent cuts. By the provision of this mechanism the machine while making the subsequent cut, moves intermittently or with 110 a step by step movement, each whose steps is equal in length to one of the dimensions such as the standard width or widths of one or more cakes of ice, and in the pause between each step, the ice between both cuts 120 is divided into a cake or cakes of standard or any other required size. This lateral cutting mechanism, so called because of its arrangement on one side of the machine, may consist of one saw or as shown in Figs. 1 125 and 2, the work may be greatly facilitated by employing a number, preferably four, saws, indicated by 119 each of which is spaced from the other for a distance corresponding to one of the dimensions, such 130

as the standard width of a cake of ice. The shaft or arbor 120 upon which these saws are mounted, is journaled in the sides 121—121 of a sectional swinging frame indicated generally by d . The sides 122—122 of the other section of said frame, are connected with the contiguous ends of the sections 121—121 by suitable means such as a bar 123, and the other ends of said sides 122—122 are pivotally mounted in upright yokes 124—124 arranged on the opposite end portions of the platform 8. Suitable means such as belts 125, trained over belt tighteners 126—126 connected to the bar 123, are employed for connecting the pulleys 127—127 on the opposite ends of the crank shaft 11 of the motor 9, with pulleys 128—128 on the opposite ends of the saw shaft 120. The inner section of the frame d , 20 or that made up of the sides 122—122, is rocked vertically by the cams 129—129 which operate on rollers 130—130 carried by the sides 122—122, and which are fixed to the cam shaft 131 which is journaled in uprights 132—132 suitably connected to the platform 8. This vertical rocking or swinging of the inner section of the frame also causes the outer section made up of the sides 121—121, to rock or swing vertically, where- 25 by, to move the saws 119 into and out of engagement with the ice. The outer section in addition to being swung or rocked vertically, is also swung or rocked laterally by suitable means such as cranks 133—133, 30 which are formed integral with or otherwise secured to the shaft 131 and suitably connected such as by links 134—134, with pins 135—135 set into or otherwise suitably secured to the side sections 121—121.

40 The throw of the cranks 133 is such as to project the saws sufficiently far to enter the ice at the initial cut, and to retract the saws through the ice to the subsequent cut and the cams are so constructed and timed as to 45 allow the saws when over the initial cut, to drop into contact with the ice, and to raise the saws after they have been moved through the ice to the subsequent cut.

Suitable means such as a sprocket 136, a 50 sprocket chain 137, and a sprocket 137^a on a sleeve 138, are employed for connecting the cam shaft 131 with a stub shaft 139 upon which the sleeve 138 is loosely mounted and which is journaled in hangers 55 140—140 depending from the platform 8, or other suitable support. A clutch 141 is splined on the shaft 139 and is operated by suitable means such as a cam, in the form of a sprocket chain 142, trained over a 60 sprocket 143 fixed to the shaft 139 and over a sprocket idler connected to the platform 8. The lateral extensions 144 on the chain 142 are adapted to force the clutch from the position shown in Fig. 8 to that shown 65 in Fig. 9, and their number is sufficient to

hold the clutch in the position shown in Fig. 9 until the saws 119 have been projected, lowered, or moved through the ice to the subsequent cut and again raised, at which time the last of the lateral extensions 70 144 will have cleared the clutch, as shown in Fig. 8, and the latter will be restored to its original position and unclutched by suitable means such as a spring-pressed operating arm 145, suitably connected to the clutch 75 and pivotally connected to the platform 8, as shown in Fig. 10.

When the machine is in motion and cutting with one of the saws 65, one of the gear wheels 18—18, will, depending upon the 80 direction in which the machine is moving, be connected with the clutch 20. As shown in Fig. 8, when the clutch is moved into engagement with one of the gear wheels, that arm of the bell crank lever 53 which is connected to the clutch through the operating rod 54, will extend obliquely to the clutch, regardless as to which of the wheels 18—18 with which the clutch engages. Now the angular-shaped end portion 146 on the said 85 arm of the bell crank, lies in the path of movement, depending on the wheel with which the clutch engages, of one of a pair of pins 147—147 depending from a lateral extension 148 carried by the operating member 90 145, when the said operating member together with the clutch 141, is moved into engagement with the sleeve 138 by means of the cam chain 142. Now if the parts be positioned as shown in Fig. 8, and the operating member 145 moved toward the bell crank, the outer pin 147 on the extension 148 will engage with one side of the angular-shaped extension 146 and rock the bell crank 95 lever together with the clutch 20, to the position shown in Fig. 9. This will have the effect of stopping the progressive movement of the machine during the time that the saws 119 are cutting the ice. After the ice has 100 been cut by the saws 119 and the projections 144 moved out of contact with the clutch 141, the spring 149 co-operates with the spring 150 for the operating lever 145 to withdraw the said operating lever and the extension 148.

110 Referring now to Fig. 8, the springs 58—58 are not perceptibly compressed when the connecting rod 56 is moved so as to operate the clutch 20. In as much as the lever which operates the rod 56, is locked 115 by its latch when the clutch is clutched with either of the wheels 18—18, the said rod 56 will not move when the bell crank is operated by either of the pins 147. But during such operation of the bell crank by 120 either of said pins, for instance, by the pin before stated, the bell crank will operate to compress one of the springs 58 when the clutch is moved to neutral position, as shown in Fig. 9, so that upon the withdrawal of 125 130

the extension 148, as previously described, the compressed spring 58 will operate to restore the bell crank and the clutch to their original positions, as shown in Fig. 8. This 5 will enable the machine to continue its progressive movement until such time as the clutch 141 and the parts connected thereto, are operated to operate the saws 119 and the bell crank lever 53. The cam chain 142 10 is so constructed as to operate the clutch 141 only at the time the machine has progressed for a distance equal in length to the combined widths of four cakes, or substantially so.

15 A suitable connection such as by means of a sprocket wheel 151, sprocket chain 152, and a sprocket wheel 153 fixed to a sleeve 154, is established between the shaft 139 and a stub shaft 155 arranged substantially co-extensive with the stub shaft 14, and journaled in hangers 156—156 depending from the platform 8, or other suitable support. A clutch 157 is splined on the shaft 155 and operatively connected by suitable means 20 such as a connecting rod 158, to an operating lever 159 fulcrumed on the rear portion of the platform 8 and adjustably secured by a latch 160 and a rack 161. A suitable connection such as by means of a sprocket wheel 30 162, a sprocket chain 163, and a sprocket wheel 164, is established between the crank shaft 11 of the motor and the shaft 155.

From the foregoing the operation of the invention will be largely understood and 35 when it is remembered that when, for instance, the forward saw in Fig. 1, is arranged to cut while the machine is moving in the direction to the right in said figure and the propeller wheels arranged so as to contact with the ice and the motor started, the machine will travel continuously for any required distance in order to make the initial cut. When a cut of sufficient length has been made, the machine is shifted laterally 40 by the mechanism before described, and until the guides enter the said cut. This done, both propelling mechanisms are rendered inactive by their respective levers and the mechanism for the side saws is thrown into 45 operation. This will have the effect of causing the side saws to cut the ice for the required distance after which the side saw mechanism is rendered inactive by unclutching the same and the clutch 20 operated so 50 as to cause the machine to go in a direction opposite to that in which is proceeded while making the initial cut. The saw on the right in Fig. 1 is then lowered, and as the machine progresses the ice between the cuts 55 made by the side saws, will be severed. The machine is now permitted to advance with only the propelling mechanism and the saws 60 in action until the side saw 119 on the extreme right in Fig. 1, is beyond the laterally cut edge of the ice for a distance 65

equal to the standard width of a cake of ice. When the machine has moved approximately half this distance the clutch controlling the side saws may be thrown into operation so that when the machine has traversed the distance before stated, it will automatically stop and the side saws go into operation. After which the machine will operate automatically to make the subsequent and lateral cuts until it arrives opposite the stationary of the initial cut, when it is shifted laterally and started in the opposite direction, as before described. 70 75

In using the modified form of harvester shown in Figs. 16 to 18 inclusive, I arrange 80 a track of any desired length, on the ice field and secure the rails 165—165 thereof by suitable means such as spikes 166—166. The supporting frame 167 is provided with suitable flange wheels 168—168 which are 85 adapted to travel on the rails 165—165 and suitable keepers 169 are arranged on one of the said rails 165 and spaced from each other for a distance corresponding to the standard width of a cake of ice, or for any 90 other suitable distance. The spring-pressed latch 170 which is suitably connected to the supporting frame 167 as shown in Fig. 20, is positioned so as to be cammed outwardly 95 by one of the cam ends 171 of the keepers as the frame advances on the track and until the latch alines with the opening of the keeper, whereupon its spring 172 will force it inwardly and lock the frame to the track, as shown in Figs. 16 to 18 inclusive. The 100 latch operating rod 173 which is pivotally connected to the frame 167 as shown in Fig. 19, is adapted when moved in one direction to force the engaging end of the latch from the keeper 169, as shown by dotted lines in 105 Fig. 20. This is done when it is desired to unlock the frame 167 in order that it may be advanced to the succeeding keeper.

The turn table 174 which is mounted upon a spindle 175 suitably secured to the frame 110 167, supports the internal combustion motor 176 whose crank shaft 177 is extended at one end so as to project considerably beyond the turn table and frame, and is journaled in a boxing 178 on the upper ends of uprights 179 which connect to a supplemental frame 180, which is connected to and extends laterally from the turn table 174. 115

The sides 181—181 of the inner section of the saw frame *e*, are connected by tie rods 120 182—182 and are turnably mounted on the shaft 177. The sides 183—183 of the outer section of the saw frame, pivot on one of the tie rods 182 and in their lower ends is journaled the saw shaft 184, one end of 125 which extends beyond one of the sides 183 and has secured thereto the circular saw 185. The belt 186 is trained over a pulley 187 fixed to the engine shaft 177 between the shafts 181 and over the pulleys of a 130

belt tightener 188, and over a pulley 189 on the saw shaft 184.

The saw frame *e* is raised and lowered by pressing on an operating handle 190 suitably secured to the inner section of the saw frame. By thus operating the said saw frame the saw 185 is moved into and out of contact with the ice.

One mode of using the device thus described, consists in arranging the parts as shown in Fig. 16 and permitting the saw to descend into contact with the ice, which is done by operating a lever 197 connected by means of a link 196, to a strut 195 which interlocks with a cross piece 198, so as to disengage the strut from the cross piece. The latch is then moved from engagement with the keeper 169 and the harvester pushed along the track and for the entire length of the track. During this operation the saw is manipulated by the handle 191 so as to cut the ice. This will make an initial longitudinal cut with respect to the track. The track is then shifted laterally from the initial cut for a distance corresponding to the length of cake desired, whereupon the harvester is caused to move as before and a subsequent cut parallel to the initial cut, is made by the saw. The turn table is then adjusted to the position shown in Fig. 18 and the outer section of the saw frame projected by forcing outwardly on the handle 191, and until the notch 192 engages with a keeper 193. This done, the saw is lowered into contact with the ice and the handle manipulated so as to draw the saw inwardly until it enters the subsequent cut. During this operation the harvester is latched to the track after which the latch is disengaged and the harvester moved until the latch engages with the succeeding keeper, whereupon a second transverse cut is made, and thus the first cake blocked out. It will, of course, be understood that the foregoing is simply descriptive of one mode of using the harvester, other and better modes may present themselves to the operator.

Although I have shown and described one embodiment of my invention it is to be understood that I am not to be limited to the specific arrangement and construction of parts since various changes may be made, within the scope of the appended claims without departing from the spirit or sacrificing any advantages of the invention.

What I claim as new is:

1. In an ice harvester, the combination with a supporting frame, and an ice cutter

carried by the frame and arranged to cut the ice longitudinally of the frame; of means for propelling the frame in the direction of the cut made by the ice cutter, means for propelling the frame in a direction at an angle to the cut made by the ice cutter, a stop carried by the frame and adapted for automatically entering the cut made by the cutting mechanism after the frame has been moved for a predetermined distance by the second named propelling means, and means for operating all of said propellers. 70

2. In an ice harvester, the combination with a supporting frame, an ice cutter carried by the frame and arranged to cut the ice longitudinally of the frame; of means for propelling the frame in the direction of the cut made by the ice cutter and adjustably connected to the opposite end portions of the frame, propelling means adjustably connected to the frame and adapted to be adjusted so as to move the frame at right angles to the cut made by the ice cutter when the first named cutting means is adjusted from contact with the ice, and a stop carried by the frame and adapted to automatically enter the cut made by the cutting mechanism when the frame has been moved a predetermined distance by the second named propelling means. 80

3. In an ice harvester, the combination of a supporting frame, propelling mechanism at the opposite end portions of the said frame, propelling mechanism connected to the supporting frame and arranged in an angular relation to the first named propelling mechanism, a motor connected to the supporting frame and reversible transmission mechanism connecting the motor with the said propelling mechanisms. 90

4. In an ice harvester, the combination of a supporting frame, propelling mechanism on the opposite end portions of the frame, propelling mechanism connected to the frame and disposed in angular relation to the first named propelling mechanism, angularly disposed ice cutters carried by the frame, a motor carried by the frame, and reversible transmission mechanism connecting the motor with the propelling mechanism and ice cutters. 100

In testimony whereof I affix my signature in presence of two witnesses.

ELMER E. STONER.
